INVENTOR

Robert G. Clyne.

BY Ralph Kalish
ATTORNEY

UNITED STATES PATENT OFFICE.

ROBERT G. CLYNE, OF ST. LOUIS, MISSOURI.

COMBINED PEN CLIP AND POCKET CHECK PROTECTOR.

Application filed August 19, 1926. Serial No. 130,237.

This invention relates to a new and useful combined pen-clip and pocket check-protector and has for its chief object the provision, as a new article of manufacture, of a device of the kind and for the purposes stated which is simple, inexpensive, compact, and durable in form and structure and which is conveniently and efficiently usable in the performance of its intended functions.

10 And with the above and other objects in view, my invention resides in the novel features of form, construction, arrangement, and combination of parts hereinafter described and pointed out in the claims.

15 In the accompanying drawing,

Figure 1 is an enlarged perspective view of a combined pen-clip and pocket check-protector embodying my invention;

Figure 2 is a longitudinal sectional view 20 of the same, illustrated in operative pen-supporting position upon the pocket-piece of a garment;

Figure 3 is a detail transverse sectional view taken approximately on the line 3—3,

25 Figure 2;

Figure 4 is an enlarged transverse sectional view approximately on the line 4—4, Figure 2.

Referring now more in detail and by reference characters to the drawing, which 30 illustrates a preferred embodiment of my invention, the main or body-portion A of my new combined pen-clip and pocket check-protector is substantially of inverted U-shape and is constructed of a suitably elongated section or strip of preferably light 35 spring steel or other suitable material, arcuately bent and doubled upon itself intermediate its ends, as at 1, to integrally comprise and provide a joined or connected pair 40 of co-operating approximately parallel legs 2, 3, transversely yieldable relatively to each other. To facilitate relative yielding movement of the legs 2, 3, and also to enhance the 45 appearance of the finished article or device, the bend or bight 1 thereof is partly offset, as shown.

Integral with the one leg 2 and located 50 thereupon adjacent the bight 1, is an outwardly-presented pair of co-operating oppositely disposed somewhat resilient and preferably skeleton arcuate wings 4, 4, suitably spaced the one from the other at their free ends and of suitable normal diametrical

dimension to receive and detachably grip 55 and hold an inserted pen B of standard or usual size and shape.

Adjacent its free end, the other leg 3 is further bent and recessed to integrally provide a so-called box-like or rectangular housing whose end walls 5, 5, are presented outwardly approximately at right angles to, and whose main or front wall 6 is approximately parallel with, the leg 3. And disposed within the recess provided by said housing and formed at its opposite ends with trunnions 7 having a bearing for rotation in the housing end-walls 5, is a toothed, knurled, or otherwise surface roughened roller 8. Formed transversely in the opposite leg 2 for accommodating and cooperation with the teeth or projections of the roller 8 in check-protecting or cutting operations, is a series of small slotted openings 9.

In use and operation, and as will be obvious from the disclosures here given, a pen B may be readily and conveniently engaged and supportingly gripped by the co-operating wings 4, 4, the pen, when so gripped and held, extending lengthwise of the device. The device as a whole may equally readily and conveniently, and either with or without a pen gripped and held thereby, be disposed in straddling supported arrangement upon a garment or pocket-piece 10, as best shown in Figure 2, the roller 8 at its teeth or projections then functioning or serving to "bite", as it may be said, the pocket-piece 10 and thereby prevent surreptitious removal or accidental loss of the device. In protecting or "cutting" a check or other such paper or document, the device is preferably detached from the garment or pocket-piece 10, the check or other such paper placed between the roller 8 and the body-leg 2, which latter then serves as a supporting base or platen, and the check and device relatively moved, when, in co-operation with the slotted openings 9 in the platen 2, the teeth or projections of the roller 8 function in suitably indenting or "cutting" and thereby protecting the check, as will be well understood. As will be noted, the wings 4, 4, at their base are also somewhat offset, as at 11, from the plane of the outer face of the body-leg 2, so that a held or gripped pen B will 100 be correspondingly supported away from

the plane of the leg and interference thereby at the slotted openings 9 with the roller 8 obviated. Preferably also the housing wall 6 is laterally enlarged to conveniently receive finger or thumb pressure in check protecting operations.

It will be evident that, while not here specifically shown, my new device may be loosely carried in a pocket or otherwise attached to the garment or pocket-piece, and it is to be understood that changes in the form, construction, arrangement, and combination of the several parts of my new device may be made and substituted for those herein shown and described without departing from the nature and spirit of my invention.

Having thus described my invention, what I claim and desire to secure by Letters Patent is:

- 20 1. As a new article of manufacture, a pocket check-protector including a connected pair of relatively yielding elongated members adapted to detachably straddle a garment-piece, one of said members having a recess within its length, in combination with a surface-roughened roller disposed longitudinally of and having a bearing for rotation upon said one member, said roller being disposed for rotation in said recess and adapted for securing engagement with the garment-piece or for protecting engagement with a check when the latter is interposed between the roller and the other of said members.
- 35 2. As a new article of manufacture, a pocket check-protector including a connected pair of relatively yielding elongated members adapted to detachably straddle a garment-piece, one of said members being provided within its length with a box-like housing whose end-walls are disposed at approximately right angles to the plane of said member, in combination with a surface-roughened roller disposed within, and having a bearing for rotation in the end-walls of, said housing, said roller being adapted for securing engagement with the garment-piece or for protecting engagement with a check when the latter is interposed between the roller and the other of said members.
- 40 3. As a new article of manufacture, a pocket check-protector including a connected pair of relatively yielding elongated members adapted to detachably straddle a garment-piece, one of said members being provided within its length with a box-like housing whose end-walls are disposed at approximately right angles to the plane of said member, in combination with a surface-roughened roller disposed within, and having a bearing for rotation in the end-walls of, said housing and adapted for securing engagement with the garment-piece or for protecting engagement with a check when the latter is interposed between the roller and the other of said members.
- 45 4. As a new article of manufacture, a pocket check-protector including a connected pair of relatively yielding elongated members adapted to detachably straddle a garment-piece, one of said members being provided within its length with a box-like housing whose end-walls are disposed at approximately right angles to the plane of said member, in combination with a surface-roughened roller disposed within, and having a bearing for rotation in the end-walls of, said housing and adapted for securing engagement with the garment-piece or for protecting engagement with a check when the latter is interposed between the roller and the other of said members.
- 50 5. As a new article of manufacture, a pocket check-protector including a connected pair of relatively yielding elongated members adapted to detachably straddle a garment-piece, one of said members being provided within its length with a box-like housing whose end-walls are disposed at approximately right angles to the plane of said member, in combination with a surface-roughened roller disposed within, and having a bearing for rotation in the end-walls of, said housing and adapted for securing engagement with the garment-piece or for protecting engagement with a check when the latter is interposed between the roller and the other of said members.
- 55 6. As a new article of manufacture, a pocket check-protector including a connected pair of relatively yielding elongated members adapted to detachably straddle a garment-piece, one of said members being provided within its length with a box-like housing whose end-walls are disposed at approximately right angles to the plane of said member, in combination with a surface-roughened roller disposed within, and having a bearing for rotation in the end-walls of, said housing and adapted for securing engagement with the garment-piece or for protecting engagement with a check when the latter is interposed between the roller and the other of said members.
- 60 7. As a new article of manufacture, a pocket check-protector including a connected pair of relatively yielding elongated members adapted to detachably straddle a garment-piece, one of said members being provided within its length with a box-like housing whose end-walls are disposed at approximately right angles to the plane of said member, in combination with a surface-roughened roller disposed within, and having a bearing for rotation in the end-walls of, said housing and adapted for securing engagement with the garment-piece or for protecting engagement with a check when the latter is interposed between the roller and the other of said members.
- 65 8. As a new article of manufacture, a pocket check-protector including a connected pair of relatively yielding elongated members adapted to detachably straddle a garment-piece, one of said members being provided within its length with a box-like housing whose end-walls are disposed at approximately right angles to the plane of said member, in combination with a surface-roughened roller disposed within, and having a bearing for rotation in the end-walls of, said housing and adapted for securing engagement with the garment-piece or for protecting engagement with a check when the latter is interposed between the roller and the other of said members.

and the other of said members, said other member being provided with a series of slotted openings for accommodating and co-operating with the surface-projections of said roller in the engagement thereof with an interposed check.

4. As a new article of manufacture, a combined pen-clip and pocket check-protector including a U-shaped body-portion comprising a connected pair of co-operating relatively yielding legs adapted to detachably straddle a garment-piece, a pair of co-operating arcuate pen-gripping wings carried by and presented outwardly from one of said legs, and a roller carried for rotation by the other of said legs and adapted for co-operation with said first leg both in securing engagement with the garment-piece and in "cutting" a check when the latter is disposed upon the inner face of said leg.

5. As a new article of manufacture, a combined pen-clip and pocket check-protector including a U-shaped body-portion comprising a connected pair of co-operating relatively yielding legs adapted to detachably straddle a garment-piece, a pair of co-operating arcuate pen-gripping wings carried by and presented outwardly from one of said legs, and a roller carried by the other of said legs and adapted for co-operation with said first leg both in securing engagement with the garment-piece and in "cutting" a check when the latter is disposed upon the inner face of said leg, said first leg being provided with a series of slotted openings for accommodating the surface-projections of said roller.

6. As a new article of manufacture, a combined pen-clip and pocket check-protector including a U-shaped body-portion comprising a connected pair of co-operating relatively yielding legs adapted to detachably straddle a garment-piece, a pair of co-operating arcuate pen-gripping wings carried by and presented outwardly from one of said legs, and a roller carried by the other of said legs and adapted for co-operation with said first leg both in securing engagement with the garment-piece and in "cutting" a check when the latter is disposed upon the inner face of said leg, said first leg being provided with a series of slotted openings for accommodating the surface-projections of said roller and said wings being offset from said first leg to support a held pen away from said slotted openings.

7. As a new article of manufacture, a pocket check-protector including first and second members of strip material connected together and transversely yieldable relatively to each other, the first member having a recess within its length, and a surface-roughened roller having a bearing for rotation upon said first member and disposed for rotation in said recess, the second mem-

ber being adapted for co-operation as a platen with said roller in the rotary movements thereof.

8. As a new article of manufacture, a pocket check-protector including first and second members connected together and transversely yieldable relatively to each other, and a surface-roughened roller carried for rotation by said first member, said second member being adapted for co-operation as a platen with said roller and having a series of apertures for accommodating and receiving the surface projections of said roller in the rotary movements thereof. 20
- 10 9. As a new article of manufacture, a second member being adapted for co-operation as a platen with said roller and having a series of apertures for accommodating and receiving the surface projections of said roller in the rotary movements thereof. 25
- 15 10. As a new article of manufacture, a

pocket check-protector adapted for detachable mounting upon a garment-piece and including first and second elongated members connected together and transversely yieldable relatively to each other, and a surface-roughened roller carried for rotation by said first member, said second member being adapted for co-operation as a platen with said roller and having a series of apertures for accommodating and receiving the surface projections of said roller in the rotary movements thereof.

In testimony whereof, I have signed my name to this specification.

ROBERT G. CLYNE.
